GESELLSCHAFT FUER DRAHTLOSE TELEGRAPHIE M. B. H., OF BERLIN, GERMANY.

MEANS FOR STRENGTHENING WEAK ELECTRICAL IMPULSES.

1,163,180.

Specification of Letters Patent. Patented Dec. 7, 1915.

Original application filed June 16, 1910, Serial No. 567,208. Divided and this application filed April 15, 1913. Serial No. 761,317.

To all whom it may concern:

Be it known that we, WILHELM SCHLOEMILCH and AUGUST LEIB, subjects of the German Emperor, and residing at Berlin, 5 Germany, have invented certain new and useful Improvements in Means for Strengthening Weak Electrical Impulses, of which the following is a specification.

The present invention relates to means 10 for strengthening weak electrical impulses which may be of an irregular kind, such as frequently occur, for example, in receiving stations for radiotelegraphy, or also for example, in ordinary telephony along continuous 15 lines.

According to the invention the weak impulses act on a relay, whose armature is damped very little acoustically and co-operates with a granular contact of the type 20 customary in microphones located in a local circuit. The one electrode of the granular contact is firmly connected with the armature. With the aid of these means it is possible to produce in the local circuit ma- 25 terially greater fluctuations of current than the primary, weak impulses acting on the relay.

The present application which is divided from our co-pending application Serial No. 30 567,208, filed June 16, 1910, covers certain features more particularly embodied in Figures 1-3 of aforesaid application. For the sake of a clear understanding of our invention we have embodied the specification of 35 aforesaid application in substance in the present one.

It is well-known, for the purpose of strengthening weak impulses to allow the same to act on a relay whose armature co- 40 operates with a microphone contact in a local circuit. In the arrangements of this kind, known heretofore, however, either the armature of the relay is very highly damped so that it possesses no sharply-defined natural 45 vibrations, or the microphone contact was not formed as a granular contact, or there was no fixed connection between the armature and the one electrode of the granular contact. For obtaining the effect aimed 50 at by the invention, it is essential, however, that the armature be damped very little acoustically and consequently possesses a sharply defined natural vibration and is simultaneously combined in the manner in-

dicated with a granular contact. Preferably 55 means are provided which enable the armature to be tuned to a definite period of vibration.

For optionally strengthening the arriving 60 impulses it is necessary to connect in series by way of the granular contacts several such strengthening relays by connecting in the contact-circuit of the first strengthening relay a second strengthening relay, and in the contact-circuit of the second strengthening relay a third relay, and so on. In this manner it is possible to strengthen many thousand-fold weak electrical impulses 65 which have been scarcely perceptible heretofore by means of a telephone placed close 70 to the ear and to make them perceptible at many meters' distance by means of a so-called loud-talking telephone. Also it is possible to record or indicate such weak tones by using suitable devices. It is essential 75 that the oscillating armature systems of the individual relays be tuned one to another.

If regular impulses are operated with, as is generally customary in radiotelegraphy, 80 all the oscillating armature systems are preferably tuned to the periodicity of the arriving fluctuations of current. If continuous or approximately continuous impulses or successions of impulses which are outside 85 the range of the acoustic vibrations perceptible by the human ear or are irregular are operated with, it is preferable to combine the receiving circuit also with a rectifier and a device for periodically varying 90 the vibrations, in which event the last-mentioned device is tuned to the period of vibration of the armature systems of the strengthening relays.

The contact-circuit or local circuit of the 95 last strengthening relay may be connected with a telephone, horn or the like, or, in the event of the arriving signals having to be recorded, with a suitable recording apparatus, such as a Morse recorder, siphon recorder, galvanometer, incandescent lamp or the like. In the latter case it is preferable not to connect the recording apparatus directly with the last local circuit but by means of suitable devices, which keep off 100 from the recording apparatus or the relay used for working the same the closed circuit current which flows in the last local

- circuit and is frequently subjected to disturbing variations. To this end, a vibration relay or a transformer or a similarly acting device may be provided which has the effect solely of transmitting the fluctuations of current, produced by the last strengthening relay, in the last local circuit to the recording apparatus or its driving relay, and stopping the passage of the closed circuit current. When employing a transformer for the above purpose, it is preferable to interpolate in the secondary circuit of the same a rectifier which converts the alternating currents in the secondary circuit into direct current impulses. The contact detector, such as a granular contact, thermo-electric cell etc., customary in radiotelegraphy has proved particularly suitable as rectifier for these relatively slow alternating currents.
- The constructional form and mounting of the strengthening relay and its oscillating armature system is also of great importance for carrying the present invention into practice. In the tests made in this direction, one definite mounting of this system, one definite form of the granular contact, and one definite insulation, regulation and mounting of the relay have proved particularly suitable, which will now be more particularly described with reference to the drawings.

Several illustrative embodiments and details of the invention are represented diagrammatically as an example in the accompanying drawings, wherein:

Fig. 1 shows a receiving connection for radiotelegraphy; Fig. 2 shows a modified mode of connecting a recording apparatus with the local circuit of the last strengthening relay; Fig. 3 shows a receiving connection which is particularly suitable for receiving continuous or approximately continuous oscillations; Fig. 4 is a cross-section through a strengthening relay, and Fig. 4^a is a detail of the latter; Fig. 5 shows the mounting of the oscillating system of the strengthening relay, and Fig. 6 the suspension of the strengthening relay. Fig. 7 represents a portion of the arrangement shown in Fig. 1 with the addition of a cutting off device for the relays.

Referring firstly to Fig. 1, *a* designates the earthed receiving aerial containing the self-induction coil *b*. A circuit branches off from this coil, in which circuit is interpolated a rectifier *c* and the strengthening relay *d*. In the illustrative embodiment an electrolytic detector, such as is customary in radiotelegraphy, is used as rectifier. A condenser *f* is in parallel with the relay. The strengthening relay *d*¹ has an armature *p*¹ which is damped very little acoustically, is preferably carried by a vibratory system stretched between two opposite points, and cooperates with the granular contact *h*¹. The

latter consists of the fixed carbon electrode *i*¹ and an electrode opposite it secured on the armature. Both electrodes are connected one with the other at their edges by a very thin flexible tissue so that a chamber, which is filled entirely or partially with grains of carbon, is formed between the electrodes. Thus the contact substantially corresponds with the granular contacts customary in microphones.

The impulses received by the receiving aerial are conducted by way of the rectifier *c* and the condenser *f* and converted into direct current impulses which act on the strengthening relay *d*¹. The latter imparts the impulses by means of its but little damped armature to the granular contact which is interpolated in a local circuit *l*¹, containing the source of current *k*¹ and produces in this circuit fluctuations of current which are materially strengthened as compared with the weak primary fluctuations. For strengthening the impulses still more, it is preferable to connect a plurality of such strengthening relays in series by interpolating a second strengthening relay *d*² in the local circuit *l*¹ of the first strengthening relay, and arranging a third strengthening relay *d*³ in the armature circuit *l*² of this relay, and so on. The local circuit of the last strengthening relay may be connected by means of the change-over switch *m* either with the telephone *n* or with a suitable recording apparatus *o*. The weak fluctuations of current received by the receiving aerial are strengthened by these means to such an extent that the fluctuations can be made acoustically perceptible by means of the telephone *n* at many meters from the telephone.

If the strengthened impulses of currents are allowed to act on a recording apparatus it is preferable to connect the last local circuit *l*³ with a vibration relay *p* which is constructed similarly to the strengthening relay. The armature *p*¹ of the relay *p* is preferably tuned to the period of vibration of the strengthening relay and carries a small platinum plate which is contacted in its rest position by a spring *p*². This spring is so tuned that its natural vibrations are very slow in comparison with the natural vibrations of the armature *p*¹. The contact *p*¹, *p*², is in a circuit which is fed by the battery *p*³ and contains the resistance *p*⁴. An ordinary direct-current relay *o*¹, whose armature circuit *o*², contains the recording apparatus *o*, is in parallel with the contact *p*¹, *p*². As long as no fluctuations occur, the direct-current relay *o*¹, remains currentless because it is short-circuited by the contact *p*¹, *p*². But as soon as the armature system *p*¹ vibrates, the contact between *p*¹ and *p*² is practically open and the direct-current relay is actuated. The purpose of the resistance *p*⁴ is

to prevent a too great current being taken from the battery p^3 in the closed circuit condition. This resistance is preferably as large as the resistance of the relay winding o^1 . In this case the vibration relay has the purpose of keeping the closed circuit current flowing in the last local circuit l^3 from the recording apparatus o or from the transmission relay o^1 provided for driving the same. If the fluctuations of current in the last local circuit are allowed to act directly on the indicating device or on the transmission relay, the defect is met with that the action of the indicating apparatus is frequently subjected to disturbances. These disturbances are due to the strong closed circuit current flowing in the last local circuit being subjected to variations owing to the disturbing influence of the granular contact or to the occurrences in the contact itself, which variations also act on the sensitive indicating device. By means of the vibrations relay p the closed circuit current flowing in the local circuit l^3 is kept away from the transmission relay o^1 and only the fluctuations of current produced in the local circuit by the strengthening relay are transmitted to the relay o^1 . The same action can also be obtained by the arrangement of a transformer as shown in Fig. 2. Here d^3 shows the last strengthening relay, whose granular contact h^3 is in the circuit of the last local circuit l^3 containing the source of current k^3 . In this local circuit is interpolated the primary coil of a transformer u , whose secondary coil is connected with a rectifier u^1 and the direct-current relay o^1 . The condenser u^2 is in parallel with the relay o^1 . The armature of this relay serves for opening and closing a local circuit o^2 , in which the indicating device o , such as a siphon recorder, relay and bell, Morse apparatus or the like, is interpolated.

The action of this arrangement is as follows: The fluctuations of current produced in the local circuit l^3 by the strengthening relay d^3 are superposed on the closed circuit current which proceeds from the battery k^3 . As the transformer u only transmits these fluctuations of current, the closed circuit current and the disturbing variation of the same is kept away from the direct-current relay o^1 . The alternate current impulses transmitted by the transformer to the secondary circuit are converted by the rectifier u^1 into direct-current impulses which are then supplied to the relay o^1 .

In all cases an ordinary contact detector can be used as rectifier, such as is frequently employed for rendering electric oscillations perceptible in radiotelegraphy. Instead of the transformer u having two coils, a so-called auto transformer having only one coil could be used.

The fluctuations of current are strength-

ened particularly well when the maximum strength of current in the individual local circuits and, correspondingly, the quantity and size of grains of the individual granular contacts are selected corresponding to their order, so that the quantity of grains in the contact h^3 is larger than that in the contact h^2 , and that in the contact h^2 is larger than that in contact h^1 .

The strengthening of the fluctuations of current is likewise all the greater, the better the individual armatures are tuned one to another. If the first strengthening relay d^1 has supplied to it a current whose number of impulses is, say, of the order of acoustic vibrations perceptible by the human ear, which is the case for example, when operating with singing sparks, according to the method well-known in radiotelegraphy, the armatures of the strengthening relays are not only tuned one to another, but also to the number of impulses to be strengthened. In this event the effect of the arrangement is particularly favorable. If the current impulses which are to be strengthened are not regular, but irregular, as is the case in the telephonic transmission of speech, it is preferable to make the natural vibrations of the armature higher than the most rapid impulse of the telephonic current which is to be strengthened.

If continuous or approximately continuous oscillations are operated with in radiotelegraphy, or if impulses whose frequencies are outside the range of the vibrations perceptible by the human ear are worked with, or impulses which follow one another irregularly, the receiving connection represented in Fig. 3 is preferably employed, in which the rectifier c interpolated in the receiving circuit co-operates with a device v for periodically varying the vibrations. This device may be an automatic interrupter, *e. g.* a so-called ticker, such as is already employed in radiotelegraphy when receiving non-damped oscillations. Such an interrupter having a rotating contact wheel is represented in the drawing. The continuous or approximately continuous oscillations received by the receiving aerial are converted by the rectifier c into redressed currents which are then converted by the interrupter v into currents of lower frequency suitable for the strengthening. These direct-current impulses then act on the strengthening relay d^1 whose armature is tuned to the interrupting device v . The local circuit l^1 of the strengthening relay can then be connected either directly, or by way of a plurality of strengthening relays d^2, d^3 with a telephone or other indicating apparatus, as Fig. 1 shows. The interrupting device v can also be so connected with the rectifier c that the impulses received by the receiving aerial are supplied only by way of

it, *i. e.* after periodic variation to the rectifier *c*. Preferably a condenser is connected in parallel with the rectifier in such manner that the received energy redressed by the rectifier *c* is stored up in the condenser. This storage also takes place while the interrupter *v* is being opened. The condenser is then discharged through the interrupting device *v* in proportion to its number of interruptions and independently of the sequence of impulses of the direct current serving for charging it.

The construction of the strengthening relay is essential for the good effect of the arrangement. As Fig. 4 shows, the fixed electrode of the granular contact is carried by a bow or holder *r* secured on a cross-bar *r*¹. The latter is mounted between springs and nuts or bolts *r*² and can be adjusted with the aid of these means relatively to the magnet. The fixed electrode of the granular contact can be moved in the neck of the bow *r* and can be set in every position by a screw *r*³. The movable electrode is formed by the armature *g* of the electro-magnet, which will be referred to hereinafter in detail. The contact face of the fixed electrode is preferably sloped so that a downwardly-enlarging space or chamber is formed for receiving the contact grains. Also, the electrodes are preferably arranged in such manner that the chamber for the grains is vertical, in order in this manner to diminish as much as possible the load on the armature due to the grains and, consequently, the damping of the armature.

The cross-bar *r*¹ adjustable relatively to the magnet serves simultaneously as support for the vibrating armature system. As Fig. 5 shows, this is formed by a wire system, to which the armature is secured in suitable manner. Preferably one single wire *s* is employed which is guided in a loop around the rollers *s*¹ *s*². The wire passes from the attachment pin *s*³ by way of the roller *s*¹ to the second attachment pin *s*⁴. The armature *g* is secured on the wire loop between the rollers *s*¹ and *s*². For the purpose of tuning the armature system the roller *s*² is held by the bearing *s*⁵ movable in the direction of the roller *s*¹ and connected with a screw *s*⁶. The latter passes through an internally-threaded member fixed on the frame of the case and in this manner enables the wire loop to be tensioned. The wires of the wire system are arranged parallel to the line connecting the centers of the faces of the magnet poles, and the armature *g* may not be materially broader than the pole faces opposite it. In this manner it is obtained that the two wires participate to the same extent and in the same sense in the vibratory movement and the armature does not tilt toward the magnet when it moves. Obviously, the wire

could be arranged and secured in another manner than that shown, and instead of the wire any other suitable member may be used for carrying the armature.

The principal feature of the arrangement of the present armature as compared with known arrangements consists in the armature system being almost acoustically without resistance and possessing a distinct natural vibration which is not damped at all, or not materially damped, by the addition of the granular contacts.

The relay is, of course, exceedingly sensitive to acoustic, mechanical and electrical disturbances. In order to protect it from mechanical and acoustic disturbances, the base plate of the magnet is secured on one or more plates *q* of cork or felt, but not by screws or similar rigid members, but preferably by an adhesive substance. The plate *q* is secured by an adhesive substance on an ebonite plate *t* and this on the support *t*¹. To the same end, current is supplied to the relay by means of soft flexible conductors *x* which do not conduct the sound, as *e. g.* 90 strands formed by plaiting a number of the finest copper wires, or slender metal ribbons, *e. g.* tinsel.

In order to keep away exterior sounds from the relay the same is preferably enclosed in a cork casing *q*¹ and surrounded, in addition, with a metal casing *z*, the purpose of which is to keep off the relay electromagnetic oscillations which might act directly from without on the relay. For regulating the sensitiveness of the relay there is arranged in a front chamber *z*¹ of the metal case an annular magnet *z*² (Fig. 4^a) which is journaled concentrically on an axle and can be rotated by means of a button or milled head *z*³. By rotating the magnet *z*², namely by changing the position of its poles relatively to the poles of the strengthening relay, the sensitiveness of the latter can be regulated.

Now it has been found that in stations for radiotelegraphy the granular contacts are impaired when the contiguous transmitting circuit is closed for the purpose of transmitting, because currents are induced in the local circuits *l*¹, *l*², *l*³, which traverse the granular contacts and frit together the grains. This defect is in part remedied by the metallic case around the relay. For completely remedying the same, it is preferable, however, to lead the local circuits of the individual strengthening relays by way of special contacts which are opened automatically when a transmitting circuit is closed. This arrangement is shown in Fig. 7. In this figure, which in general arrangement is the same as shown in Fig. 1, on either side of the granular contact device *z*¹, *z*², *z*³ a switch contact 1 is provided, which can be closed by means of switch knives 2,

The switch knives are fastened to a common rod 3 to which is connected contact 5 which closes the transmission current. Rod 3 may be operated by electromagnet 4 or also 5 through handle 6. Before messages are transmitted, the rod is lifted whereby as well the relays are disconnected from their respective circuits as also simultaneously contacts 5 are closed.

10 In order to protect the relay against mechanical shocks, to which the carrying frame of the relays is subjected, the relays are suspended cardanically, as shown in Fig. 6. As this figure shows, a plurality of relays d^1 , d^2 , are secured to a common carrier t^1 , which is suspended movably toward all sides by means of a rod t^2 , a portion of a sphere t^3 and a bearing t^4 . A hollow india-rubber ring t^5 , distended by air or another elastic 20 body is preferably placed between the portion of the sphere and the bearing in order to absorb shocks in a vertical direction from the relays and simultaneously to damp the oscillation of the relays.

25 We claim:

1. In an arrangement for strengthening weak electrical impulses, means for receiving weak impulses, a relay comprising an electromagnet and an armature suitably 30 supported so as to permit its swinging freely with its own period, means for varying the period of the armature, two electrodes and a granular contact therebetween, one of said electrodes being fixed to said 35 armature and of small mass to still permit the swinging of said armature with its own period, a rectifying device acted upon by the weak impulses, a device for periodically varying said weak impulses, the armature 40 of said strengthening relay being tuned to the periodicity of the variation device.

2. In an arrangement for strengthening weak electrical impulses, means for receiving weak impulses, a relay comprising an 45 electromagnet, an armature suitably supported so as to permit its swinging freely with its own period, means for varying the period of the armature, two electrodes and a granular contact therebetween, one of said 50 electrodes being fixed to said armature and of small mass to still permit the swinging of said armature with its own period, a rectifying device acted upon by the weak impulses, a device for periodically varying 55 said weak impulses, the armature of said strengthening relay being tuned to the periodicity of the variation device, and a condenser adapted to be charged by the rectified currents and discharged by the variation device.

3. The combination with an apparatus 60 for perceiving and strengthening weak elec-

trical oscillations, of means for converting the strengthened direct current impulses into alternating currents, a rectifier for converting the alternating currents into direct currents and a recording apparatus.

4. The combination with an apparatus 65 for perceiving and strengthening weak electrical oscillations, of a transformer converting the strengthened direct current impulses into alternating currents, a rectifier for converting the alternating currents into direct currents and a recording apparatus.

5. The combination with an apparatus 70 for perceiving and strengthening weak electrical oscillations, of a transformer for converting the strengthened direct current impulses into alternating currents, a contact-detector of the character used for high frequency vibrations for re-converting the alternating currents into direct currents and a recording apparatus.

6. The combination with an apparatus 75 for perceiving and strengthening weak electrical oscillations, of a transformer converting the strengthened direct current impulses into alternating currents, a rectifier for re-converting the alternating currents into direct currents, a relay connected in 80 series with said rectifier and the secondary winding of said transformer, a condenser in parallel with said relay, and a recording apparatus.

7. In an arrangement for receiving and 85 strengthening weak electrical impulses, means for receiving weak impulses, a relay comprising an electro-magnet, an armature, suitably supported so as to permit its swinging freely with its own period, a rectifying 90 device acted upon by the weak impulses, a device for periodically varying said weak impulses, the armature of said strengthening 100 relay being tuned to the periodicity of the variation device.

8. In an arrangement for receiving and strengthening weak electrical impulses, means for receiving weak impulses, a relay comprising an electromagnet, an armature suitably supported so as to permit its swinging freely with its own period, a rectifying device acted upon by the weak impulses, a device for periodically varying 110 said weak impulses, the armature of said strengthening relay being tuned to the periodicity of the variation device, and a condenser adapted to be charged by the rectified currents and discharged by the variation device.
